UNITED STATES PATENT OFFICE

166,466

MEDALLION

Edward E. Herrmann, South Bend, Ind., assignor
to The Studebaker Corporation, South Bend,
Ind., a corporation of Delaware

Application January 2, 1951, Serial No. 13,648

Term of patent 3½ years

(Cl. D14—6)

To all whom it may concern:

Be it known that I, Edward E. Herrmann, a citizen of the United States, residing at South Bend, in the county of Saint Joseph and State of Indiana, have invented a new, original, and ornamental Design for a Medallion, of which the following is a specification, reference being had to the accompanying drawing, forming a part thereof.

In the drawing:

Figure 1 is a front elevational view of a medallion showing my new design;

Figure 2 is an end elevation of the medallion of Figure 1;

Figure 3 is a plan view of the medallion of Figure 1; and

Figure 4 is a vertical sectional view taken centrally of the medallion shown in Figure 1.

I claim:

The ornamental design for a medallion, as shown.

EDWARD E. HERRMANN.
